[57] CLAIM

The ornamental design for a rattle, as shown and described.

DESCRIPTION

FIG. 1 is a front view of a rattle showing my new design;

FIG. 2 is a top view thereof;

FIG. 3 is a right side view thereof; and,

FIG. 4 is a vertical sectional view taken on the staggered line 4—4 of FIG. 2 thereof.

The bottom view is a mirror image of the top view;

The rear view is a mirror image of the front view;

The left side view is a mirror image of the right side view.
